Attorneys.

UNITED STATES PATENT OFFICE.

GEORGE N. HEIN, OF SAN FRANCISCO, CALIFORNIA.

APPLIANCE FOR USE BY ANÆSTHETISTS.

Application filed May 16, 1924. Serial No. 713,753.

To all whom it may concern:

Be it known that I, GEORGE N. HEIN, a citizen of the United States, residing at city and county of San Francisco, and State of California, have invented certain new and useful Improvements in Appliances for use by Anæsthetists, of which the following is a specification.

In the performing of surgical operations 10 in oral and nasal cavities under a general anæsthetic—especially one of nitrous oxide and oxygen, gas is unsatisfactory due to the inability to control the supply of air which the patient may take i. e. that supply exclusive 15 of the amount given by the anæsthetists. This condition is occasioned by the patient being able to breathe both through the nasal passage and through the mouth, and necessitates the administering of 20 what may be termed a heavy anæsthetic, such as ether, for a comparatively light or minor operation.

The present invention relates to an apparatus designed for controlling the respiratory passages by blocking the esophagus and tracheal orifices from the oral and nasal cavities and establishing artificial communication with the respiratory organs of the patient through this blocking means, enabling 25 the administering of an anæsthetic through the artificial passage provided. Also as a barrier against foreign bodies or pus laden mucus being inhaled or swallowed during the operation. By the use of the 30 present apparatus, considerable saving of anæsthetics and all volatile anæsthetics may be had, at the same time enabling an efficient control of the administering of the anæsthetics.

40 By the use of the apparatus the oral and nasal cavities may be separately blocked from the pharyngeal cavities and esophagus and tracheal orifices, or the anæsthetic may be administered through the nose, the only 45 desire being to block the mouth to prevent foreign bodies and secretion from entering the respiratory passage when the operating field is confined to the oral cavity only.

The invention consists in providing a 50 damming member of relatively soft yieldable material, preferably expansible, to conform to the size and shape of the orifice or cavity to be blocked, and preferably to a device having a variable diameter in both circumference and cross section, and in mounting the dam as to enable the same to be

readily positioned for use when expanded to engage the walls dammed, and when it is desired to remove the same, to enable the pressure to be released permitting the device 60 to be withdrawn from the cavity instantly.

The invention consists further in providing an apparatus having an orifice extending in rear of the dam member, and affording a connection or communication between 65 the rear of the dam member and the atmosphere, enabling the supply of an anæsthetic therethrough.

With the above mentioned and other objects in view, the invention consists in the 70 novel construction and combination of parts hereinafter described, illustrated in the accompanying drawings, and set forth in the claims hereto appended, it being understood that various changes in the form, proportion, size and minor details of construction 75 within the scope of the claims may be resorted to without departing from the spirit or sacrificing any of the advantages of the invention.

To more fully comprehend the invention, reference is directed to the accompanying drawings, wherein:—

Figure 1 is a longitudinal sectional view illustrating in dotted lines the projection of 85 the periphery of the damming member beyond the peripheries of the confining walls.

Figure 2 is a sectional view on line 2—2 of Figure 1.

Referring more particularly to the drawings wherein like characters of reference designate corresponding parts, the numeral 1 indicates an elongated tubular body of relatively small diameter, the same preferably consisting of a small rubber or metallic 90 tube, the passage 2 in which is open at its opposite ends as at 3 and 4. One end of the body 1 is of substantially bell mouthed or flanged structure 5 affording a wall projecting radially from the end of the body 1. 100 The opening 4 is disposed off center in the wall 5, as is clearly indicated in Figure 3. The opposite end of the body 1 is provided with a handle 6 and embracing said body for frictional sliding movement thereon is a 105 movable wall member 7 disposed in opposing relation to the wall or flange 5. In elevation the member 7 corresponds substantially to the configuration of the member 5 except with its curved face 8 disposed facing 110 the curved face 9 of the member 5. From the wall member 7 extends an arm 10 pref-

erably in close contact with the surface of the member 1 as in Figure 1, and the arm at its rear carries a handle 11 lying adjacent to the handle 6 on member 1.

5 In the embodiment of the invention illustrated, there is positioned between the walls 5 and 7 surrounding the portion of the tubular member lying therebetween a suitable elastic member 12 preferably of ring formation, and the embodiment illustrated is adapted for inflation when it is desired to expand the same, as in dotted lines 13, to force its periphery a greater distance beyond the peripheral edges of the walls 5 10 and 7. Communicating with the interior of the inflatable elastic member 12 is a tubular connection 14 preferably extending parallel with the members 1 and 10 and passing through apertures in the handles 11 and 6, which provide a support therefor. At the point of passage through the handles 11 and 6 the connection 14 is preferably of metallic structure 15, and to the end of the structure 15 is connected a hose 16 of an inflating bulb 20 or member 17, there being interposed between the bulb and hose 16 a relief valve 18 of any well known structure.

While I have illustrated member 12 as an inflatable bladder, it is to be understood that 30 any form of relatively soft elastic material capable of being projected beyond the peripheral edges of the walls 5 and 7 may be employed.

When in use, the pressure is released by 35 the opening of valve 18, handles 11 and 6 are moved from each other and the appliance is inserted in the oral cavity of the patient. When the member 12 is in the desired position, the handle 11 is moved from the handle 6 until such time as the periphery of the member 12 assumes the desired 40 position. The member 12 is then inflated by the actuation of the bulb 17 until it projects a sufficient distance beyond the edges of 45 the walls 5 and 7 and tightly engages the tissue walls against which it is to bear during the damming operation. When positioned for blocking the esophagus and tracheal orifices from the oral and nasal 50 cavities, or blocking the oral cavity from other respiratory passages, the tube 2 provides an artificial breathing passage for the patient, and to the outer end of this tube 55 may be attached the anesthetic supply, controlled in any suitable manner for delivery

to the patient, thus with the nasal cavity blocked off, the tube 2 is the only means through which respiration by the patient may be had, and therefore it is an easy matter to control the supply of gas and oxygen 60 or other inhalation anesthetic to the patient as desired.

I claim:

1. An apparatus for the described purpose comprising an inflatable means for positioning through the oral cavity for engaging the walls thereof to interrupt communication between the oral and nasal cavities and the esophagus and the tracheal orifices, and means comprising opposing wall members 70 between which said inflatable means is positioned for limiting the distortion of said means in opposite directions with its periphery free for distortion, and a tube extending laterally from said inflatable means and 75 providing artificial breathing communication between the atmosphere and a point in rear of said means.

2. An apparatus for the described purpose comprising a tubular member flanged at one 80 end, a flanged member cooperating with the tubular member with its flange movable to and from the flange of said tubular member, and an elastic inflatable member projecting beyond the peripheries of the flange 85 members and held therebetween, said flanged members affording confining walls for the sides of said elastic member.

3. An apparatus for the described purpose comprising opposing wall members 90 movable to and from each other, an elastic inflatable member held therebetween, with its periphery free to expand beyond the peripheries of the wall surface, and a tubular support for said wall members extending at 95 substantially right angles from the face thereof.

4. An apparatus for the described purpose comprising an elastic inflatable member, confining wall surfaces movable to and from each other and between which said elastic member is held with its periphery free to project beyond the peripheries of the wall members, and a tubular support mounting one confining wall and on which the other 100 105 confining wall slides, said support being formed of relatively rigid material.

In testimony whereof I have signed my name to this specification.

GEORGE N. HEIN.
